UNITED STATES PATENT OFFICE.

WALTER E. SWINSCOE AND GEORGE L. COLLINS, OF WACO, TEXAS.

ICE-WEIGHING DEVICE.

Application filed April 17, 1922. Serial No. 553,999.

To all whom it may concern:

Be it known that we, WALTER E. SWINSCOE and GEORGE L. COLLINS, citizens of the United States, residing at Waco, in the county of McLennan and State of Texas, have invented certain new and useful Improvements in Ice-Weighing Devices, of which the following is a specification.

This invention relates to new and useful improvements in ice weighing devices and particularly that type which is installed within a refrigerator.

The object of the invention is to provide means in connection with the ice supporting shelf or tray of a refrigerator for weighing the ice when the same is placed in the refrigerator.

A further object is to provide an exterior indicator which will register the weight of the ice at all times and the exact weight of the ice in the refrigerator may be ascertained without opening the same.

A construction designed to carry out the invention together with other features of the invention will be hereinafter described.

The invention will be more readily understood from a reading of the following specification and by reference to the accompanying drawings, in which an example of the invention is shown and wherein:

Fig. 1 is a partial front elevation of a refrigerator equipped with a device constructed in accordance with our invention, a portion being indicated in dotted lines,

Fig. 2 is an elevation of the mechanism removed from the refrigerator,

Fig. 3 is a perspective view of a portion of the weighing device,

Fig. 4 is a perspective view of the ice tray,

Fig. 5 is a detail of the indicator,

Fig. 6 is a detail of one of the trunnion supports, the parts being slightly separated, and

Fig. 7 is an enlarged detail of the connection between balancing beams.

In the drawings the numeral 10 a rectangular metal supporting frame which may be suitably mounted in the ice chamber of

a refrigerator or ice box. Any suitable sup-

porting means may be used in place of the frame. On each side near each end the frame has fulcrumed therein, four hook members 11 having eyes 12 depending below the frame. The members are mounted to swing freely and receive in their eyes, the ends of transverse rock shafts 13, which latter have knife edges 14 engaging in said eyes. The shafts have within the frame, laterally projecting loops 15, those of one shaft being directed toward those of the other shaft. The ends of these loops have upwardly directed knife edges 16 as is best shown in detail in Fig. 6.

A rectangular ice tray 17 of suitable construction is disposed within the frame 10 with sufficient space therebetween to permit freedom of movement of the tray. The tray has depending trunnions 18 notched to fit on the knife edges 16, so that as the tray is moved up and down the loops will be swung and the shafts rocked. One of the shafts has a forwardly directed balance beam 19 provided with a depression having an upwardly directed knife edge 20; while the other shaft has a rearwardly directed balance beam 21 provided with a laterally directed finger 22 at its inner end resting upon the knife edge 20.

An angular bracket 23 fastened on the front end of the frame 10 overhangs the forward end of the beam 19 which extends under and beyond the front end of the frame. A coiled spring 24 is provided with a tensioning screw 25 which extends up thru the bracket and receives an adjusting nut 26. The spring has a depending hook 27 in which the forward end of the beam 19 rests. It will be seen that the beams are swung downwardly by the loops 15 against the tension of the spring. The spring counter-acts the weight placed upon the tray 17 and swings the beams upwardly when the weight is reduced.

The knife edges 14, 16 and 20 make for a very sensitive poise and the spring may be adjusted to a nicety, whereby the device will weigh accurately. On the forward end of the beam 19 I provide a laterally directed arm 28 which supports the end of a

crank arm 29 provided on one end of a shaft 30. A weight 31 or other means is mounted on the crank arm to hold the same down upon the arm 28. The shaft 30 is placed transversely of the frame 10 and parallel of the front wall of the refrigerator, but within the same. Short standards 32 support the shaft 30 and collars 32' fastened on the said shaft prevent longitudinal displacement of the same.

A counter shaft 33 is mounted in brackets 34 vertically in the refrigerator and is supported by a collar 35 fastened thereon and engaging the lower bracket. A bevel gear 36 on the lower end of the shaft 33 meshes with a bevel gear 37 on the adjacent end of the shaft 30. A bevel gear 38 on the upper end of the vertical shaft meshes with a bevel gear 39 mounted on a jack shaft 40 supported in a box 41 mounted in the wall of the refrigerator. A gear 42 fastened on the shaft 40 within the box meshes with a pinion 43 fastened on an indicator shaft 44. A hand 45 mounted on the outer end of the shaft 44 is disposed in front of a dial 46 mounted on the outside of the refrigerator wall.

Normally the hand 45 occupies an upright position and registers with zero as is shown in Fig. 1. When a block of ice or the like is placed upon the tray 17 the loops 15 are swung downwardly, whereby the balance beams 19 and 21 are swung downwardly thru the rocking of the shafts 13, the finger 22 contributing the downward pressure of the beam 21 to the beam 19 thru the agency of the knife edge 20. The beam 19 thus sustains the entire load which is exerted against the tension of the spring 24.

When the beam 24 is depressed the arm 28 is lowered, whereby the weight 31 is permitted to swing the crank arm 29, which remains constantly in contact with the arm 28. The shaft 30 is rocked by the crank arm in a clockwise direction and thru the means of the gears 36 and 37 rotates the vertical shaft 33 which rotates the shaft 40 in a clockwise direction. The gear 42 thru the pinion 43 rotates the shaft 44 in a counter-clockwise direction, whereby the hand is likewise swung.

The weight indicating numerals on the dial 46 are placed in a counter-clockwise order and the parts of device are proportioned and related so that the hand 45 will be swung the proper distance to register with the numeral indicating the weight of the block of ice which has depressed the tray 17. When the weight upon the tray is reduced the beams 19 and 21 will be swung upwardly and if the weight 31 was not employed the crank arm, which is raised by the arm 28, would remain elevated and the indicator would not be operated, when

the arm 28 was again lowered. It is to be understood that the indicating means permits of various changes and locations.

Various changes in the size and construction of the various parts as well as modifications, may be made within the scope of the appended claims.

What we claim, is:

1. In an ice weighing device for installation within a refrigerator, a pair of fulcrumed rocking members, an ice supporting tray mounted upon said members for rocking the same when loaded, a pair of balance beams in engagement and attached to said rocking members to be swung thereby, a counter-balance connected with one of the beams an arm extending from the counter-balanced beam, a crank shaft connected with said arm, and an indicator connected with and operated by the crank shaft. 75

2. In an ice weighing device for installation within a refrigerator, pivoted supporting hooks, transverse rock shafts pivoted in the hooks, loops directed toward each other from the rock shafts, an ice tray having 90 depending trunnions supported in the loops, balancing beams connected with the rock shafts and engaged with each other, a coiled spring under tension and supporting one of the beams, and an indicator having 95 operative connection with one of the beams.

3. In an ice weighing device for installation within a refrigerator, pivoted supporting hooks, transverse rock shafts pivoted in the hooks, loops directed toward each other from the rock shafts, an ice tray having 100 depending trunnions engaging in the loops, a balancing beam extending from one of the shafts and having a depression provided with a knife edge, a second balancing beam extending from the other rock shaft and provided with a finger resting upon the knife edge of the first beam, a coiled spring under tension supporting the outer end of the first beam, indicator operating means connected with the first beam, and an indicator connected with the said means. 105

4. In an ice weighing device for installation within a refrigerator, a pair of balancing beam members, an ice tray supported on said members, a coiled spring supporting one of said beam members, an arm extending laterally from said last named beam member, a crank shaft, a crank arm carried by the shaft and resting upon the arm, means for holding the crank arm constantly in engagement with the arm, and an indicator operated by the crank shaft. 115

5. In an ice weighing device for installation within a refrigerator, a pair of pivoted rock shafts, a supporting frame, hooks pivoted in the frame and having depending eyes, knife edges on the shaft engaging in the eyes of the hooks, loops extend- 120

125

130

ing laterally from the shafts and having knife edges, an ice tray having depending trunnions mounted on the knife edges of the loops, a pair of parallel balancing beams 5 extending oppositely from the shafts, one of said beams having a knife edge and the other having a lateral finger resting upon the knife edge, a coiled spring mounted on the frame and supporting the beams having the knife 10 edge, means tensioning said spring, an arm projecting from said last named beam, indi-

cator operating means connected with said arm, and an indicator connected with said means.

Signed and witnessed at Waco, Texas, 15 this 13th day of April, A. D. 1922.
